[57] CLAIM

The ornamental design for a combined covered casserole and serving cradle, substantially as shown and described.

DESCRIPTION

FIG. 1 is a side elevational view of a combined covered casserole and serving cradle showing my new design;
FIG. 2 is a top plan view thereof;
FIG. 3 is a side view thereof;
FIG. 4 is a bottom plan view thereof;
FIG. 5 is an exploded perspective view thereof;
FIG. 6 is a side elevational view of a second embodiment of my design for a combined covered casserole and serving cradle which differs from the first embodiment only in the relative proportions thereof; and
FIG. 7 is a side elevational view of a third embodiment of my design for a combined covered casserole and serving cradle which differs from the first and second embodiments only in the relative proportions thereof.
